UNITED STATES PATENT OFFICE.

WILLIAM J. A. LONDON AND ROBERT C. ALLEN, OF HARTFORD, CONNECTICUT, ASSIGNEES TO THE TERRY STEAM TURBINE COMPANY, OF HARTFORD, CONNECTICUT, A CORPORATION OF CONNECTICUT.

TURBINE.

1,229,490.

Specification of Letters Patent. Patented June 12, 1917.

Application filed September 19, 1912. Serial No. 721,126.

To all whom it may concern:

Be it known that we, W. J. A. LONDON, a subject of the King of England, and resident of Hartford and State of Connecticut, and whose post-office address is Hartford, Connecticut, and ROBERT C. ALLEN, a citizen of the United States, and resident of Hartford and State of Connecticut, and whose post-office address is Hartford, Connecticut, have invented new and useful Improvements in Turbines, of which the following is a specification.

This invention relates particularly to the fastening of the blades or vanes in the rotor and has for its object to provide a simple, inexpensive and secure means for accomplishing this purpose.

Referring to the drawings:

Figure 1 is a perspective view of the rotor made in accordance with our invention.

Fig. 2 is a cross sectional view of the blade.

Fig. 3 is a cross sectional view of the root of the blade.

Fig. 4 is a cross sectional view of the packing filler.

Fig. 5 is a view looking on the end of a blade positioned in the rotor.

Referring to the drawings *a* denotes the body of the rotor the periphery of which is transversely slotted at regular intervals, as indicated at *b*, holes being drilled as indicated at *c* to form an enlargement at the bottom of each slot. 10 denotes the blade or

35 vane. 11, the root of the blade; and 12, a filler one side of which is shaped to fit the root of the blade, the other side being flat to fit against one wall of the slot in the rotor. The filler is placed against the root of 40 the blade and then both are inserted in a slot in the rotor and driven down until the overhanging portion of the blade is set firmly against the edge of the rotor. The length of the root is slightly greater than the depth of 45 the slot with the result that when the blade is driven down into position the lower end of the root is bent at an angle to its main portion, forming a secured lock. The outer

or upper ends of the several blades are fitted into a shroud in any usual or convenient manner. The construction here described is extremely simple and provides a very secure and rigid fastening for the blade.

We claim as our invention:

1. In a blade fastening device the combination with a rotor having transverse slots in its periphery, of a blade having a root of irregular cross section adapted to fit into said slot, and a filler adapted in shape to fit in said slot at one side of the root. 50

2. In a device of the character described, the combination with a rotor having transverse slots in its periphery, of a blade provided with a root of reduced size and of irregular cross section, a filler adapted in 55 shape to fit the irregular side of said root and with the root to closely fill the slots in the rotor, said blade overlying said filler. 60

3. In a device of the character described, the combination with a rotor having transverse slots in its periphery, of a blade and means for fastening said blade to said rotor comprising a blade root and a filler having correspondingly shaped contacting faces and adapted to fit snugly in the slots. 70

4. In a turbine a rotor having its periphery transversely slotted, blades overlying said slots and seated against the face of the rotor, each blade provided with a root fitting said slot, and means for bending the end 75 of said root when the blade is driven into position, to lock the blade in place.

5. In a turbine a rotor having transverse peripheral slots the walls of which are inclined at the bottom, blades overlying said 80 slots and seated against the face of the rotor, each blade being provided with a root adapted to fit within the slots and be deflected by the said incline when the blade is seated, and a relatively shorter filler located in each slot 85 back of the roots.

6. A blade for turbine rotors comprising a main body portion and a root provided with a flat front face and an irregular rear face.

7. In a turbine a rotor having transverse 90 peripheral slots inclined at the bottom,

blades overlying said slots and seated against the face of the rotor, a root formed integrally with the blade, a filler block fitting against said root, said filler block and root filling said slots and said root being relatively longer than said filler block and adapted to contact with and be deflected by the inclined wall of said slots when said

blade is properly seated, to lock the blade in position.
